CROSSING COMPOSED OF VIGNOLES RAILS

Application filed September 27, 1929, Serial No. 395,624, and in Germany October 19, 1928.

Whereas it has become known in grooved rail-crossings to make these crossings wear proof by insertion of double-cheek groove wedges or other insert pieces made of special steel, Vignoles rail crossings have been made hitherto merely of rails of normal quality.

This invention has for its object to make such crossings, composed of Vignoles rails of normal quality, wear proof by suitable means at those points which are specially submitted to wear, and to thereby considerably lengthen the durability of such Vignoles rails crossings.

15 According to the invention this object is obtained by fitting in a crossing, in which the crossing point is formed on the one side by two joining rails, whereas the rails, lying on the other side, are bent and extend on the 20 side of the crossing point formed by the joining rails, the inner side of the heads of the bent rails with an insert of wear proof material, for instance manganese steel, and by providing on the crossing point formed by 25 the joining rails a cap of wear proof material gripping over both these rails.

The wear proof pieces inserted into the bent rails may be preferably arranged so that they undercut the rail heads on the outer 30 side of the crossing and so that the inner edges of the bottom faces of the same are welded together with the rails on the inner side on which they form the head of the rail.

By this undercutting of the insert piece in 35 the rail head on the side turned away from the wheel flange it becomes possible, to fix the insert pieces with only one single welding seam which, owing to its low position, is never touched by the wheel flanges.

40 The cap of wear proof material gripping over the joining rails may also be connected at its lower edges with the rails by welding.

By the connection of these wear proof insert pieces in crossings composed of Vignoles 45 rails the durability, and thereby the security of service of such crossings, are considerably increased as all parts specially submitted to strong wear are made of wear-proof material.

50 An embodiment of the invention is illus-

trated by way of example in the accompanying drawing.

Fig. 1 shows a crossing in top plan view.

Fig. 2 is a section on line 2—2 of Fig. 1.

Fig. 3 is a section on line 3—3 of Fig. 1.

The crossing point is formed on the one side by the joining rails *a* and *b*, on which a cap *c* made of wear-proof material is placed over a suitable length after proper fashioning of the rail heads. The other side of the crossing is formed by the bent rails *d* and *e* which, in the range of the crossing proper, have wear-proof inserts *f* and *g* undercutting the rail heads on the outer side.

The cap *c* as well as the inserts *f* and *g* have horizontal or almost horizontal bottom surfaces in order to ensure a secure resting and uniform pressure transmission. The welding seams for the fixation of the inserts or of the cap on the rails are designated by *h*.

The cap *c* may also be secured by rolling to the rails *a* and *b*.

I claim:—

A crossing composed of Vignoles rails the crossing point of which is formed on the one side by joining rails, the two rails on the other side being bent off and extending side by side with the rails forming the crossing point, comprising a cap of wear-proof material like manganese steel of $\square$ -shaped section covering both joining rails of the crossing point, the lower edges of said cap being fixed on the rails by welding; and an insert of wear-proof material provided on the inner side of the head of each bent rail, said inserts undercutting the rail heads on the outer side, the inner edge of their flat bottom face being welded on the said rails.

In testimony whereof I have hereunto set my hand.

FRITZ WERTHMAN.
